LIQUID-ELEVATING APPARATUS

Jesse C. Reed, Dayton, Ohio

Application September 20, 1944, Serial No. 555,009

7 Claims. (Cl. 103—72)

This invention relates to liquid-elevating apparatus, and more particularly to that type of apparatus in which an endless belt or cable is trained over an upper pulley while the lower part of the belt or cable depends into and enters the body of liquid which is to be elevated, the lower run of the belt or cable supporting a freely revolving counterweighted pulley which is movable in vertical guides to maintain the belt or pulley under desirable tension.

The object of the present invention is to provide improved means whereby the efficiency of such liquid-apparatus is structurally improved, simplified and the efficiency thereof increased over prior arrangements.

For a further understanding of the invention, reference is to be had to the following description and the accompanying drawings, wherein:

Fig. 1 is a vertical sectional view, partly in side elevation, of liquid elevating apparatus formed in accordance with the present invention;

Fig. 2 is a front elevational view thereof, the associated well being shown in vertical section;

Fig. 3 is a detail vertical sectional view taken through the upper or liquid discharge end of the apparatus;

Fig. 4 is a top plan view of the apparatus with the endless belt shown in horizontal section;

Fig. 5 is a fragmentary vertical sectional view taken through the upper or driving pulley of the apparatus;

Fig. 6 is a vertical sectional view taken through the lower pulley and the weighted tensioning means for the elevator belt;

Fig. 7 is a front elevational view of the lower pulley member and its associated weight structure;

Fig. 8 is a similar view disclosing the lower pulley member in another position of operation.

Referring by numerals to the accompanying drawings which illustrate a practical embodiment of my invention, the numeral 10 designates the bore of a subterranean well or shaft, containing in the bottom thereof a column or body of liquid to be elevated. At the ground level around the bore or shaft, there is provided a frame structure, indicated at 11. This frame structure embodies a vertically disposed hollow pedestal 12 which supports at the upper end thereof a discharge head 13 having a liquid outlet spout 14. The open top of the head 13 is normally closed by a hinged lid or cover 15, which may be held in its position of closure by the threaded fastening means indicated at 16.

The side walls of the head 13 are formed with

bearings 17 for the rotatable reception of an operating shaft 18. In this instance, the shaft 18, exteriorly of the head, is coupled, as at 19, with the armature shaft of an electric motor 20. It will be understood, however, that any other suitable drive mechanism may be employed for imparting rotation to the operating shaft 18. The motor 20 may be mounted on a bed 21, which may be adjusted longitudinally of the frame structure 11 by means of the screw devices shown at 22.

Fixed for rotation on the shaft 18 and arranged within the head 13 is an operating pulley 23, the latter having flanged sides 24 and the outer peripheral surface of the pulley between the sides 24 is provided with shallow depressions or ruffles 25. Passing over the pulley 25 is the upper run of a flexible endless carrier 26, which preferably is in the form of a belt of rubberized material, although the carrier may take the form of a series of cables. This belt is disposed vertically in the well bore or shaft 10 and the lower run of the belt, which is submerged in the water or other liquid contained in the bottom of the bore, is trained over a weighted pulley 27. The shaft 28 of the pulley 27 is journaled in a clevis 29, the depending stem 30 of the clevis being pivotally connected as at 31 with an equalizer bar 32. This bar, in turn, is provided with a depending ear 33 perforated to receive a pintle 34 which is carried by the spaced apertured ears 35 of a rocker member 36. This member is situated in a recess 37 provided in the upper end of a carrier-tensioning weight structure 38, the opposite longitudinal ends of the rocker member being formed with aligned fulcruming studs 39 which are received in openings formed in the upper part of the weight structure.

The weight structure consists of a plurality of 40 removably interfitting bars 40 by means of which the total weight of the structure may be increased or diminished by the additional removal of bars to govern the tensioning forces applied to the carrier 26 as may be found necessary in practice. The sides of the weight structure are grooved in order that said structure may be received by spaced vertical guide rails 41. The upper ends of these rails are secured to the column or pedestal 12, and the rails are spliced together as indicated at 42 so that they may be of suitable length convenient for handling, and yet extended as necessary to meet the requirements of wells of different depths.

To raise and lower the weight structure cables 43 have their lower ends secured to the opposite

ends of the equalizer bar 32. These cables extend upwardly and have their upper ends wrapped around and secured to drum elements 44 carried by a rotatably journaled cross shaft 45, which is suitably supported in connection with the pedestal 12. The outer end of the shaft 45 may be provided with a hand crank 46 and the rotation-controlling ratchet wheel and pawl 47. By this arrangement, the operating positions of the weighted pulley 27 in the bottom of the well may be controlled and, also, the pulley may be raised to the top of the well for inspection or repair purposes thereof.

Usually, the pulley 27 is arranged above the weight structure 38, as shown in Figs. 1 and 2. This is the preferred arrangement where there is a substantial height of liquid in the bottom of the well bore. If, however, the height of the liquid in the well bore should be comparatively low or shallow, the weight structure may be reversed as disclosed in Fig. 8, in which the pulley 27 is located in a recess 48 provided in the lower member 49 of the weight structure. By this arrangement, shallow wells may be operated effectively.

As the belt or carrier is advanced in the direction indicated by the arrows A in Fig. 3, water or other liquid is carried upwardly on the surfaces of the upwardly advancing run of the carrier and as the same travels around the pulley 23, the liquid is flung centrifugally from the surfaces of the belt and pulley and deposited on the inclined bottom wall 50 of the support 14. In such elevators, there has been a considerable back drain of the elevated liquid into the well, particularly the liquid carried by the under surface of the belt as the same passes around the upper pulley. By means of the depressions or ripples 25 of the upper pulley, the water carried by the under side of the belt travels outwardly of the pulley toward its flanged sides 24 and beyond the confines of the side edges of the belt, so that as the pulley rotates, this previously trapped liquid is also discharged centrifugally from the upper pulley and deposited on the inclined discharge wall 50, with the result that there is but a negligible amount of loss in the volume of liquid raised to the upper pulley.

The pedestal 12 carries an insert section 51 having opposite sides thereof recessed as at 52 to provide guides for slideable bearing blocks 53. These blocks rotatably support the end shaft extensions of a roller 54, which bears on the return or downwardly moving side of the carrier belt 26. If the well bore or shaft 10 is of considerable diameter, for example, in excess of 8 inches, the roller need not be employed, but when the well bore is of smaller diameter, the roller is used to move the ascending and descending runs of the belt closer together in order that they may be accommodated in wells of reduced diameter and yet to permit of a relatively enlarged standard size pulley at the top of the well, and where a pulley of relatively large diameter operated much more efficiently and effectively than one of reduced diameter.

The bearing blocks 53 are engaged by means of screws 55 adjustable in threaded openings provided in the walls of the insert section 51, the said screws being exteriorly accessible so that the operating positions of the roller 54 may be regulated with convenience.

The principal advantage of the apparatus here disclosed resides in the fact that the same can elevate an equal volume of water or other liquid

with an operating motor of lower horse power rating than can be accomplished with conventional motor driven pumps. The apparatus is essentially simple and may be used for the elevation of many kinds of liquids having a wide viscosity range. Also, liquids which contain solids in suspension can be readily handled as well as those which contain chemicals injurious to most metal pumps, such as those encountered in many coal mines.

The apparatus is so constructed that there is very little or nothing to get out of order and adjustments can be readily made from the top of the well. The compound pivots provided at 31, 34 and 36 prevent binding of the weight structure on its guide bars as well as permitting the lower pulley to assume its natural operating position under all conditions of operation. The construction of the upper pulley is such that substantially all liquid which reaches the plane of the upper pulley is discharged from both surfaces of the carrier belt and the upper pulley itself, minimizing losses heretofore encountered as a result of the dropping of the elevated liquid back into the well. Through the use of the shaft 45 and its associated cables 43, adjustment in the operating positions of the lower pulley and its associated weight structure may be readily effected from the top of the well and, likewise, the weight structure and lower pulley may be elevated for inspection or removal from the well in a simple and convenient manner.

I claim:

1. Liquid-elevating apparatus of the character set forth comprising a casing having a liquid outlet, a drive pulley rotatably supported in said casing adjacent to said outlet, a rigid frame depending from said casing into the body of liquid to be elevated, a weight structure slidably carried by said frame, a weight structure slidably carried by said frame, a windlass rotatably mounted on said casing, cable means connected with said windlass and from which said weight structure is suspended for raising and lowering movement on said frame, a second pulley connected with said weight structure, an endless belt passing around said pulleys, and means for rotating said drive pulley.

2. Liquid-elevating apparatus of the character set forth comprising a casing having a liquid outlet, a rigid frame depending from said casing into the body of liquid to be elevated, a weight structure slidably carried by said frame, a windlass rotatably mounted on said casing, cables trained around and connected to said windlass, an equalizer bar joined with said cable means and pivotally connected with said weight structure for turning movement about relatively perpendicular axes, a drive pulley at the top of said frame, a second pulley connected with said weight structure, an endless flexible belt passing around said pulleys, and means for rotating said drive pulley.

3. Liquid-elevating apparatus of the character set forth comprising a casing having a liquid outlet, a drive pulley rotatably supported within said casing adjacent to said outlet, a rigid stationary frame depending from said casing into a body of liquid to be elevated, a weight structure composed of a plurality of interconnected bar elements slidably mounted in said frame for vertical movement relative thereto, a second pulley connected with said weight structure, an endless flexible belt trained around said pulleys, and means for rotating said drive pulley.

4. A liquid-elevating apparatus of the character set forth comprising a casing having a liquid outlet, a drive pulley rotatably supported in said casing adjacent to said outlet, said pulley having the peripheral surfaces thereof formed with a multiplicity of liquid-conducting grooves, a rigid frame depending from said casing into the body of liquid to be elevated, a weight structure slidably carried by said frame, a second pulley connected with said weight structure, endless flexible means passing around said pulleys, and means for rotating said drive pulley.

5. A liquid-elevating apparatus of the character set forth comprising a casing having a liquid outlet, a drive pulley rotatably supported in said casing adjacent to said outlet, a rigid frame depending from said casing and adapted to have the lower end thereof submerged in a body of liquid to be elevated, a weight structure mounted for vertical sliding movement in said frame, a second pulley connected with said weight structure, an endless belt passing around said pulleys, and a horizontally adjustable guide member carried by said casing and engageable with one of the runs of said belt to control the spacing of the opposed belt runs.

6. Liquid-elevating apparatus of the character set forth comprising a casing having a liquid out-

let, a drive pulley rotatably supported in said casing adjacent to said outlet, a rigid frame depending from said casing and adapted to have the lower end thereof submerged in a body of liquid to be elevated, a weight structure carried by and movable vertically of said frame, a windlass rotatably mounted in said casing, a rocker member joined with said weight structure for turning movement about a substantially horizontal axis, an equalizer bar pivoted to said rocker member for turning movement about a horizontal axis arranged at right angles to the axis of pivotal movement of said rocker member, cable means connected with said windlass and with said equalizer bar, a yoke pivotally connected with said equalizer bar, a second pulley carried by said yoke, an endless belt passing around said pulleys and maintained under tension by said weight structure, and means for rotating said drive pulley to impart movement to said belt.

7. Liquid-elevating apparatus as defined in claim 6 and wherein the weight structure is composed of a plurality of interconnected bar members in which the outer ends of said bar members are grooved for guided sliding movement on said frame.
